VELOCITY MODULATION TUBES

Jean P. Voge, Paris, France

Application February 17, 1951, Serial No. 211,506

9 Claims. (Cl. 315—6)

The present invention relates to electron discharge tubes of the velocity modulation type, and more particularly to a novel form of klystron tube having a wide band of frequencies over which it can be tuned without alteration of the geometrical shape of its resonant cavities.

This application is a continuation in part of my co-pending application Serial No. 725,682, filed January 31, 1947, now Patent No. 2,614,234.

The klystron tube of my invention includes two hollow body resonators or resonant cavities of essentially prismatic or cylindrical shape (in the broad geometrical sense of the word "cylindrical"). The two cavities, termed "buncher" and "catcher" in the terminology of the art, function as wave guides within which systems of standing waves are established by electromagnetic fields which have the same frequency in both, but which are of different phase wave lengths in the two. The systems of standing waves are generated and maintained, at least in the catcher cavity, by an electron beam of ribbon shape, i. e., having a two-dimensional extension, which is projected through the two cavities across a "gap" in each separating electron-permeable areas or grids in two opposite faces of the cavities. In passing through the cavity, the electron beam follows trajectories which are perpendicular to the long dimension of these resonators, i. e., to the generators or elements of their cylindrical or prismatic surfaces, with the breadth of the electron beam parallel to such generators or elements. In a preferred embodiment, the breadth of the electron beam is in both cavities substantially equal to an integral but different number of quarters of the phase wave length of the standing wave fields existing in the cavities.

Prior art devices of the klystron type use reentrant chambers or cavities having three principal shapes: reentrant prismatic, reentrant cylindrical in the form of figures of revolution about an axis perpendicular to the cavity gaps, and reentrant cylindrical in the form of figures of revolution about an axis parallel to and remote from said gaps.

Klystrons of the first and second types have pencil-shaped beams of electrons and klystrons of the third type have centrifugal or centripetal plane starlike shaped beams, i. e., beams emitted by an axial cathode structure and collected by a ring-shaped collector, or emitted by an annular cathode element and collected by an axial collector. In all three types of tube, the ultra-high frequency input to the catcher cavity produces across its gap an electromagnetic field the electric vector of which is directed along the line of travel of the electrons. The gap areas of the resonators, i. e., the areas of the portions of opposite faces of the resonators which approach each other to form the grids, are so scaled that the electromagnetic field is near its peak value over the entire area at the gaps and, in particular, has no nodes in the region of the gaps. In other words, the electron stream traverses the electromagnetic fields of the cavities near the location where the standing wave amplitudes are maximum and over paths which, as to all dimensions of such

2

paths, are very much smaller than the phase-wavelength of the oscillations in the resonant cavities.

I have determined by analysis and experiment that by using as cavity resonators prismatic conducting cavities traversed by a flat ribbon-shaped electron beam whose width is parallel to the generators of the cylindrical surfaces to which the cavities conform, the beam having in a preferred form substantially the same width as the height of the cavities, and by dimensioning the cavities in such a way that the buncher cavity oscillates over an even number of quarter phase wavelengths in the direction parallel to these generators and by dimensioning the catcher cavity so that it oscillates over an odd number of quarter phase wavelengths, the bandwidth can be substantially increased.

It is therefore a major object of my invention to provide an ultra-high frequency electron discharge device of the velocity modulated electron beam type having novel internal proportions and having unusual bandwidth characteristics.

A further object of my invention is to produce an electron velocity modulated tube of large bandwidth without the necessity of corrugated flexible or otherwise deformable walls for the cavity resonators.

A further object of my invention is to provide a novel ultra-high frequency device of the velocity modulation type wherein a ribbon-shaped electron beam of two-dimensional extension is projected transversely through substantially the total height of the hollow prismatic resonator means.

A further object of my invention is to provide a prismatic reentrant buncher cavity resonating on an even multiple of quarter-wavelengths and a prismatic reentrant catcher cavity of substantially the same height as the buncher and resonating on an odd multiple of quarter-wavelength, both chambers being traversed by a wide ribbon-shaped electron beam over their height.

The foregoing and other objects of my invention will be best understood from the following description of a preferred embodiment thereof, reference being had to the accompanying drawings wherein like numerals of reference indicate similar parts throughout the several views and in which:

Fig. 1 is a schematic view of a klystron tube intended to illustrate certain theoretical considerations on which the invention is based;

Figs. 2 and 3 are respectively a vertical longitudinal section and a horizontal cross-section of an electron velocity modulation tube embodying my invention, Fig. 3 being taken on line 3—3 of Fig. 2 and Fig. 2 being taken on the line 2—2 of Fig. 3;

Figs. 4 and 5 are respectively perspective views of the buncher and catcher cavities of the klystron of Figs. 2 and 3; and

Fig. 6 is a diagram for the calculation of the cross sectional dimensions of the cavities in klystrons according to my invention.

Referring to Fig. 1 which is idealized, and using the notation of Arthur E. Harrison, "Klystron Tubes," McGraw-Hill, 1947, the instantaneous voltage across the input gap 1 between grids 11 and 12 of the buncher cavity is:

$$E = E_1 \sin \omega_1 t_1$$

where E_1 is the peak value of the radio-frequency voltage, ω_1 the angular velocity and t_1 the time of departure of an electron from the mid-plane of the buncher gap. The fundamental component of the radio-frequency current at the output of cavity 2, behind drift space 3, is

$$i_2 = 2I_0 I_1(x) \sin \omega_1 (t_2 - t_1)$$

where I_0 is the number of electrons entering the cavities

per unit time, J_1 is the Bessel function, x the bunching parameter, t_2 the time of arrival in the output gap for an electron leaving the input gap at time t_1 , and T_0 the transit time from buncher to catcher for an electron with average velocity. Maximum current i_2 occurs when the bunching parameter has a value of 1.84.

Let R_s be the shunt resistance of the catcher resonator and C the capacity between its grids 4 and 5, spaced d centimeters apart. Then,

$$C = 0.088 \cdot 10^{-12} \frac{A}{d} \text{ farads} \quad (1)$$

where A is the area of the grids in square centimeters (perpendicular to the plane of Fig. 1). The Q of cavity 2 will then be given by

$$Q = C \omega_1 R_s \quad (2)$$

and the output voltage by:

$$E_2 = R_s i_2 = \frac{Q}{C \omega_1} i_2 \quad (3)$$

For a given amplification factor (i. e. a given E_2) and for i_2 maximum (bunching parameter equal to 1.84) and a given angular frequency ω_1 , the Q factor will be proportional to C as shown by Equation (3).

The invention is concerned with increasing the bandwidth of the tube. To this end it would be desirable to reduce Q by reducing C . Equation (1) implies that this can be achieved by reducing A or by increasing d . Neither of these solutions is desirable, however, because a reduction of A reduces the intensity I_0 of the beam and hence the intensity of i_2 , while increasing d introduces perturbations into the operation of the tube in view of the effect of transit time between the grids 4 and 5.

Instead, let the grids 4 and 5 be considered as forming the two conductors of a transmission line of length l_2 transverse to the direction of propagation of the beam and supporting a system of standing waves. The line will have a characteristic impedance Z_c and is short-circuited at its end 6. The impedance of the line at the end opposite the short circuit is

$$Z_s = j Z_c \tan \beta_2 l_2$$

Here β_2 is the phase constant in the geometric propagation constant of the line. See "Principles of Radar," McGraw-Hill, 1946, Equation 96, Chapter 8. The line looks like a theoretically infinite reactance if

$$\beta_2 l_2 = \frac{\pi}{2}$$

like an inductive reactance when

$$\beta_2 l_2 < \frac{\pi}{2}$$

and like a capacitive reactance when

$$\beta_2 l_2 > \frac{\pi}{2}$$

In place of

$$R_s = \frac{Q}{C \omega_1}$$

one obtains $R_s = Q Z_c \tan \beta_2 l_2$.

For a given R_s , Q may be reduced by selecting $\beta_2 l_2$ as nearly to

$$\frac{\pi}{2}$$

as desired. According to the present invention one chooses for the catcher a mode of vibration such that the length of the cavity traversed by the beam is equal

to an odd number of quarter phase wavelengths, i. e., so that $\beta_2 l_2$ is equal to

$$(2K+1) \frac{\pi}{2}$$

K being an integer.

According to a further feature of the invention the output coupling loop is located close to the open-circuited end of the grids 4 and 5 and the catcher cavity is closed off at this end by a rounded chamber of low height, i. e. of low extension along the length of the generators of the main catcher cavity cylinder or prism.

It is known that the bunching parameter is proportional both to the drift distance and to the peak value 15 of the input modulation voltage (voltage across the gap of the buncher cavity). In order to have a peak value of E_1 in the buncher cavity substantially higher than the peak value of the voltage in the input line which is coupled to the buncher cavity, one chooses for the buncher 20 cavity a mode of oscillation such that the "height" or length of this cavity which is traversed by the width of the electron beam is equal to an even number of quarter phase wavelengths, and the input line coupling loop is located at a node of the oscillations, i. e. either close to the bottom wall or to the top wall of the buncher, which is closed at both ends by a conducting plate or wall. In 25 this way E_1 can be increased, permitting a reduction in the drift distance without changing the bunching parameter.

30 In Fig. 1, there is shown at 7 a wide, flat, ribbon-shaped electron beam having a width equal to the common heights l_1 and l_2 of the grids of the cavities 1 and 2 and of very small extension in the direction perpendicular to the plane of the figure. 8 represents the standing wave pattern of the electric field in the buncher cavity as a half wave with nodes at the short-circuited terminals 9 and 10 of the grids 11 and 12. 13 represents the standing wave pattern of the electric field in the catcher cavity as a quarter wave with a node at the short-circuited terminal 6 of grids 4 and 5 and with an anti-node at the open circuited end of these grids.

40 The input coupling loop 14 is located close to a node of the sinusoidal standing wave pattern 8 and the output coupling loop 15 is located close to the maximum amplitude of the sinusoidal standing wave pattern 13. It is 45 to be borne in mind, of course, that the dimensions of the grids are small in directions perpendicular to the plane of the figure.

50 Referring now to Figs. 2 and 3, 201 represents a vacuum tight envelope of some suitable material such as glass. Inside the envelope is an electrode assembly 202 supported by a pair of standards 203 which are sealed through the wall of envelope 201 and constitute lead-in conductors to the cavity resonators for connecting them 55 to a suitable unidirectional source of potential 204, shown as a battery.

The electrode structure 202 comprises a cathode heater 205 which may for example be in the form of a helix fed from local source 206 through one pair of lead-in wires 60 207.

65 A long flat-shaped cathode 208 has its exterior face (Fig. 3) coated with a mixture of barium and strontium or of other suitable thermionically emissive material. Cathode 208 is supported between insulating spaces 209 and 210 and is connected to lead-in conductor 211.

70 212 is a line-focussing and accelerating electrode connected to lead-in conductor 213 and thence to a suitable voltage positive with respect to the cathode, supplied for example by a tap on the battery 204 as shown.

To the right of the collector 214 the glass tube envelope 75 is replaced by a metallic membrane 216 sealed to the glass and provided with cooling fins 217.

The buncher and catcher resonators 218 and 219 are of rectangular reentrant cross section. These cavities are bounded by a common thick metal bottom wall 220, outer

lateral walls 221 and 222, a common separative wall 223, front wall 224 and rear wall 225 and by walls 227 and 228. Walls 224, 223 and 225 are provided with flat rectangular slots extending, in the embodiment shown, over the total height of the cavities and aligned linearly with each other and with cathode 208 and collector 214. The cavities are thus prismatic cylinders whose directrices or cross sections are rectangles with a rectangular reentrant portion, the reentrant portions of the two cavities facing each other.

In the rectangular opening 226 in wall 223, a pair of conducting plates 227 and 228, parallel to walls 221 and 222, define a corridor or drift space axially aligned with cathode and collector. This corridor and cavity 218 are further bounded by common top-wall 229.

The cavity 219 is extended in an upward direction, i. e. in the direction of the generators, by means of a cavity of rectangular cross-section 230. The cavity 230 is without reentrant portion and is of low height or short extension in the direction of the prismatic elements. The cross-sectional dimensions of the cavity 230 are larger than those of the cavity 219 and it is closed at the top by means of a top wall 231. The transition between the lateral walls of cavity 219 and the lateral walls of the cavity 230 is effected by means of a rounded portion 232 best seen in Fig. 5.

All the walls bounding the cavity resonators are of copper or some good electrically conducting material or may be plated with a good conducting material.

Upper and lower insulating spacers 209 and 210 surround the cavity assembly and are affixed to the top and bottom walls 229 and 220 by screws 237.

On either side of the rectangular slots in the walls 224 and 225, and at either side of the ends of the field-free drift space corridor bounded by plates 227 and 228, there are provided vertical rod-like supports 238 of small diameter supported parallel to the generators of the prismatic cylindrical cavity volumes. Fine wires are wound on these rods to form grids 233 and 234 for the buncher and 235 and 236 for the catcher. All four grids are therefore of substantially flat rectangular shape and have the same shape and area as the cathode 208 and collector 214.

Input loop 239 extends through an opening in cavity 218 and is located near its top-wall 229. One of the ends of the loop is connected to the inner side of wall 221 of cavity 218.

Output loop 240 extends through an opening in cavity 219 and is located at the non-short-circuited portion of grids 235 and 236, i. e. adjacent the beginning of flared wall portion 232. Loop 240 has one end connected to the inner side of wall 221 of cavity 219.

Loops 239 and 240 are provided with conducting extensions 241 and 242, which are surrounded by tubular conductors 243 and 244, the inner ends of which are fastened to the outer side of wall 221 around the openings through which said loops project. Conductors 243 and 244 are sealed through the wall of envelope 201 and gas tight bushing seals 245 and 246 are likewise provided within them. Conductors 243 and 241 constitute the input concentric transmission line and conductors 244 and 242 constitute the output concentric transmission line through which the ultra high frequency power is effectively led from the tube.

If the tube is to be operated as an amplifier the input line is connected to the source of signals to be amplified while the output line is connected to a load. If the tube is to be operated as an oscillator the input and output lines are connected together by a transmission line of suitable length, all as is well known to those skilled in the art.

By way of example, there will now be considered the design of a klystron amplifier according to my invention intended to operate on a 10 centimeter wavelength and having prismatic resonant cavities 8 centimeters in height. Let the letter l represent the height of the cavities, i. e.

their length as sections of prismatic cylindrical guides, $2c$ their width perpendicular to the trajectory and to the width of the electron beam; b their depth in the direction of the beam trajectories, and $2a$ the width of their reentrant portions perpendicular to the width of the beam (see Figs. 4 and 5). Let δ represent the length of the gap. With the subscript 1, these quantities refer to the buncher, and with the subscript 2 they refer to the catcher.

The cavity 218 must possess dimensions such that it will oscillate in a system of standing waves having a half phase wavelength in directions parallel to its generators or elements. Since the height is to be 8 centimeters, the phase wavelength $\lambda_{\phi 1}$ is to be 16 centimeters and the cut-off wavelength λ_{c1} is given by

$$\frac{1}{\lambda_{c1}^2} = \frac{1}{\lambda^2} - \frac{1}{\lambda_{\phi 1}^2} = \frac{1}{10^2} - \frac{1}{16^2}$$

Consequently $\lambda_{c1} = 12.64$ cm.

Fig. 6 is a graph in which the quantity

$$X = \frac{\lambda c}{2b}$$

for reentrant prismatic cavities is plotted as a function of the parameter a/b for different values of the parameters

$$\frac{c-a}{b} \text{ and } \frac{\delta}{b}$$

The curves drawn in solid lines correspond to

$$\frac{c-a}{b} = 0.4$$

Curve 601 is for

$$\frac{\delta}{b} = 0.3, 602 \text{ for } \frac{\delta}{b} = 0.2$$

and

$$603 \text{ for } \frac{\delta}{b} = 0.1$$

The curves drawn in dotted lines correspond to

$$\frac{c-a}{b} = 0.8$$

Curve 601' is for

$$\frac{\delta}{b} = 0.3, 602' \text{ for } \frac{\delta}{b} = 0.2$$

and

$$603' \text{ for } \frac{\delta}{b} = 0.1$$

If one chooses

$$X = \frac{2c_1}{2b_1} = 5, \text{ then } b_1 = 1.25 \text{ cm.}$$

55 If, moreover,

$$\frac{a_1}{b_1} \text{ is to be } 0.4, \text{ then } a_1 = 0.5 \text{ cm.},$$

and if

$$\frac{c_1 - a_1}{b_1}$$

is to be 0.8, then $C_1 = 1.5$ cm.

The abscissa .4 and the ordinate 5 intersect at the point 65 604 on the curve 602' for which

$$\frac{\delta_1}{b_1} = 0.2$$

and accordingly

$$\delta_1 = 0.25 \text{ cm.}$$

The cavity 218 is thus completely determined.

In its prismatically reentrant portion traversed by the beam, the cavity 219 must oscillate in a system of standing waves one quarter of a phase wavelength long parallel

to the generators of the cavity. Since its height or length is 8 centimeters, its phase wavelength $\lambda\phi_2$ will be 32 centimeters and its cutoff wavelength λ_{c2} will be given by

$$\frac{1}{\lambda_{c2}^2} = \frac{1}{\lambda^2} - \frac{1}{\lambda\phi_2^2} = \frac{1}{10^2} - \frac{1}{32^2}$$

or

$$\lambda_{c2} = 10.52 \text{ cm.}$$

In order to employ for both cavities the same lateral exterior walls and the same walls for the drift space corridor, i. e. to make 221, 222, 227 and 228 common to the two cavities, one chooses

$$a_1 = a_2 \text{ and } c_1 = c_2$$

By choosing

$$\frac{c_2 - a_2}{b_2} = 0.4$$

b_2 is determined as 2.5 cm.

Then

$$\frac{a_2}{b_2} = 0.2 \text{ and}$$

$$X = \frac{\lambda_{c2}}{2b_2} = 2.10$$

The abscissa .2 and the ordinate 2.1 intersect at the point 605 through which passes the solid line curve 606 corresponding to

$$\frac{\delta_2}{b_2} = 0.34$$

This gives $\delta_2 = 0.85$ cm. and the cavity 219 is completely determined as to its prismatically reentrant portion.

The magnitude of the short dimension e for the rectangular cavity 250 which closes the cavity 219 at its upper extremity is chosen so as to give to the cavity 230 a cutoff wavelength $2e$ greater than 10 centimeters. For example, $e = 6$ cm. will be a suitable value. The two portions 219 and 230 of the catcher cavity are coupled by means of the curved boundary 232.

Operation of my klystron is as follows:

Referring to Figs. 2 and 3, heater 205 raises cathode 208 to a temperature at which it emits electrons. These electrons are accelerated under the action of the positive potential applied to electrode 212 into cavities 218 and 219 and pass through the gap between grids 233 and 234. Across this gap, electrons are modified as to velocity by the input field in chamber 218 and continue their travel through the field-free corridor between plates 227 and 228 with the electrons having normal or unaffected speed overtaking previously dispatched slower electrons and, in turn, being overtaken by speeded-up electrons started at a later moment. In accordance with classical theory, the proper bunching of electrons takes place across gap between grids 235 and 236. The electrons accordingly represent a concentration of energy in the said gap and give up energy to resonator chamber 219 which oscillates with a reduced Q without sacrificing the shunt resistance as set forth above.

In the foregoing descriptive specification I have described a particular embodiment of the principles of my invention, but these principles are capable of application in many alternative forms which will be evident to those skilled in the art. For example, I have described the buncher cavity as resonating upon half a wavelength and the catcher cavity as resonating upon a quarter-wavelength but it will be seen that the former may oscillate upon any even multiple of quarter-wavelengths and the latter upon any odd multiple of quarter-wavelengths.

I claim:

1. An electron discharge tube of the velocity modulation type comprising a buncher cavity substantially enclosed by conducting material and conforming substan-

tially to a prism whose principal section is a reentrant polygon, a pair of parallel electron-permeable grids of similar and equal rectangular shape one formed in a reentrant face of the buncher cavity and the other formed in a face of said buncher cavity opposite the said reentrant face, said grids extending in the direction of the buncher cavity prism elements over that proportion of the height of the buncher cavity prism represented by a simple fraction whose numerator and denominator are small integers, an input coupling loop in the buncher cavity located distant from one end thereof by a simple fraction of the said prism height, the numerator and denominator of the said fraction being small integers, said numerator being a multiple of two and said denominator being a multiple of four, a catcher cavity substantially enclosed by conducting material and conforming except at one end substantially to a prism whose principal section is a reentrant polygon, the cross-section of said catcher cavity being different from the cross-section of said buncher cavity, a pair of electron-permeable grids in opposite faces of the prismatic portion of the catcher cavity of substantially the same size, shape and disposition as the buncher cavity grids, a non-reentrant supplementary cavity of greater cross section than that of the prismatic portion of the catcher cavity closing one end of the catcher cavity, means to support the buncher and catcher cavities parallel with their grids in alignment, means to generate an electron beam of two-dimensional extension having a width substantially equal to the height of said grids, means to accelerate said beam through all of said grids, an output coupling loop in the catcher cavity located adjacent the junction between the supplementary cavity and the prismatic portion of the catcher cavity, said catcher cavity having in its prismatic portion such cross section and height that an electromagnetic field of the frequency of a field which in the buncher cavity will have a phase wave length of whose quarter the height of the buncher cavity is an even multiple will in the catcher cavity have in propagation down the catcher cavity a phase wave length of whose quarter the prismatic height of the catcher cavity is an odd multiple.

2. An electron discharge tube of the velocity modulation type including buncher and catcher cavities, a cathode and a collector electrode, input coupling means linking with the volume of the buncher cavity and output coupling means linking with the volume of the catcher cavity, the buncher cavity conforming substantially to a cylindrical solid, a pair of electron-permeable grids occupying substantially equal areas on opposite faces of the buncher cavity cylinder, said areas having in the direction of the generators of the buncher cavity cylinder a dimension substantially equal to an even number of quarters of the phase wave length of a field of given frequency vibrating in a fundamental mode of the buncher cavity cross section, the height of the buncher cavity cylinder being substantially equal to an even number of quarters of the said buncher cavity phase wave length, said input coupling means being located in the buncher cavity adjacent a node of the standing wave pattern of radiation having said buncher cavity phase wave length, the catcher cavity including a re-entrant cylindrical cavity closed at one end by a right section of said catcher cavity cylinder and closed at the other end by a non-reentrant supplementary cavity, the catcher cylindrical cavity having such length and cross section that radiation of the said given frequency vibrating within the catcher cavity according to the said mode has a phase wave length whose quarter is an odd submultiple of the cylindrical catcher cavity length, and said output coupling means being located remote from said one end of the catcher cylindrical cavity an odd number of quarters of said catcher cavity phase wave length.

3. An electron velocity modulation discharge device comprising in combination narrow rectangular cathode and collector electrodes, buncher and catcher reentrant

prismatic cavity resonators of substantially the same height with each other and with said cathode and collector electrodes but of different cross sections, said resonators being adapted to have a ribbon-shaped electron stream emitted by said cathode pass through narrow electron permeable sections in said resonators extending over the total height thereof, said buncher cavity being short-circuited at both ends and said catcher cavity being short-circuited at one end only, a non-re-entrant supplementary cavity coupled to the other end of the catcher cavity, the buncher cavity being adapted to oscillate in a system of standing waves having a half-phase-wavelength equal to its height and the catcher cavity being adapted to oscillate in a system of standing waves having a quarter-phase-wavelength equal to its height, and means for applying input energy to the buncher and for extracting output amplified energy from the catcher.

4. A velocity modulation electron discharge device comprising in combination narrow rectangular cathode and collector electrodes, buncher and catcher re-entrant prismatic cavity resonators of different cross sections but of substantially the same height with each other and with said cathode and collector electrodes and adapted to have a ribbon-shaped electron stream emitted by said cathode pass through narrow electron permeable sections extending over the total height thereof, the buncher resonator being short-circuited at both ends and the catcher resonator being short-circuited at one end only, a supplementary cavity resonator coupled to the other end of said catcher resonator, the buncher resonator being adapted to oscillate in a system of standing waves having a half-phase-wavelength equal to its height and the catcher resonator being adapted to oscillate in a system of standing waves having a quarter-phase-wavelength equal to its height, means for applying input energy to said buncher resonator located near one end thereof, and means for extracting output amplified energy from the catcher resonator located near the junction of the catcher and supplementary resonators.

5. An electron discharge tube comprising two cavity resonators each conforming at least in part substantially to a cylinder whose principal section is a plane figure having a re-entrant portion, the principal sections of said two resonators being of unequal areas, each said resonator having on one of its re-entrant faces and on an exterior face a substantially rectangular electron-permeable grid, all four of said grids extending over substantially equal lengths parallel to the elements of the cylinders, the first of said resonators being short-circuited at both ends, the second of said resonators being short-circuited at one end only, a supplementary cavity resonator coupled to the other end of said second cylindrical resonator, said cylindrical resonators being supported with their cylindrical elements parallel and with said four grids in line with each other, a cathode adjacent a first one of said cylindrical resonators adapted to generate a ribbon-shaped electron beam having a width substantially equal to the length of said grids, and means to accelerate said beam through all of said grids, the first of said cylindrical resonators having a cross section adapted to provide over the length of said first cylindrical resonator for energy of a frequency at which said first cylindrical resonator resonates a path substantially equal to an even number of quarters of the phase wave length of such energy in propagation lengthwise of said first cylindrical resonator and said second cylindrical resonator having a cross section adapted to provide over the length of said second cylindrical resonator for energy of the said frequency a path substantially equal to an odd number of quarters of the phase wave length of such energy in propagation lengthwise of said second cylindrical resonator.

6. An electron discharge tube according to claim 5 including input coupling means located distant from one end of the first cylindrical resonator by an even number of quarters of the phase wave length of energy of said

frequency in propagation lengthwise of said first cylindrical resonator and including output coupling means located distant from one end of said second cylindrical resonator by an odd number of quarters of the phase wave length of energy of said frequency in propagation lengthwise of said second cylindrical resonator.

7. An electron discharge tube comprising two cylindrical cavity resonators of substantially the same height and of different re-entrant cross sections, the first of said resonators being short-circuited at both ends and the second being short-circuited at one end thereof only, a supplementary cavity resonator coupled to the other end of said second cylindrical resonator, said supplementary cavity having a greater cross section than said second cylindrical resonator, said cylindrical resonators having each two electron-permeable grids formed in opposite faces thereof, said grids extending over substantially the total height of said cylindrical resonators, means supporting said cylindrical resonators with their grids in line and parallel to each other, a cathode adjacent a first one of said cylindrical resonators adapted to generate a ribbon-shaped electron beam having a width substantially equal to and aligned with the length of said grids, means to accelerate the beam through all of said grids, means to couple a radio frequency field into said first cylindrical resonator, and means located adjacent the junction between the second cylindrical resonator and the supplementary resonator to couple out radio frequency energy from the second of said cylindrical resonators.

8. An electron discharge tube comprising a buncher cavity resonator conforming at least in part substantially to a prism having lateral, top and bottom walls of conductive material and having a re-entrant cross-section adapted to provide over the length of said buncher resonator between its top and bottom walls for energy of a frequency at which said buncher resonator resonates a path substantially equal to an even number of quarters of the phase wave length of such energy in propagation lengthwise of said buncher resonator, a catcher cavity resonator conforming at least in part substantially to a prism of the same length as said buncher resonator, said catcher resonator having lateral and bottom walls of conductive material and being open-ended at its top and having a re-entrant cross-section adapted to provide over the length of said catcher resonator for energy of said frequency a path substantially equal to an odd number of quarters of the phase wave length of such energy in propagation lengthwise of said catcher resonator, a non-re-entrant supplementary cavity resonator of conductive material joined to said catcher resonator at the top thereof, said supplementary resonator having a greater cross-section than that of said catcher resonator, four electron-permeable grids disposed two on each of the buncher and catcher resonators and extending over substantially the total lengths of said buncher and catcher resonators parallel to their prismatic elements, means to support said buncher and catcher resonators with their prismatic elements parallel and with said four grids in line, a cathode adjacent said buncher resonator adapted to generate a ribbon-shaped electron beam having a width substantially equal to the common length of said buncher and catcher resonators, means to accelerate the electron beam from said cathode through all of said grids, means to couple a radio frequency field into said buncher resonator, and means located adjacent the junction between the supplementary resonator and the catcher resonator to couple out radio frequency energy from the catcher resonator.

9. An electron discharge tube according to claim 8 in which the means to couple the radio frequency field into the buncher resonator is located distant from one end of the buncher resonator by an even number of quarters of the phase wave length of energy of said frequency in propagation lengthwise of said buncher resonator.
